SLIDE BUCKLE

Jerome R. La Vigne, Waterbury, Conn., assignor
to The Waterbury Buckle Company, Water-
bury, Conn., a corporation of Connecticut

Application April 10, 1940, Serial No. 328,811

3 Claims. (Cl. 24—197)

The present invention relates to improvements in buckles and more particularly to improvements in slide-buckles, i. e., buckles in which one member slides with respect to another member to grip a strap or the like.

One of the objects of the present invention is to provide a superior slide-buckle so constructed and arranged as to combine effectiveness of holding power with low cost for manufacture.

Another object of the present invention is to provide a superior slide-buckle so constructed and arranged as to be assembleable with ease and rapidity.

A further object of the present invention is to provide a superior slide-buckle so constructed and arranged that a strap or the like may be attached to one of the members while the same is conveniently available and prior to the assembly of such member with a companion or complementary buckle member.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a view in front elevation of a slide-buckle embodying the present invention and shown as organized with a strap and a button-loop suitable for use in connection with overalls;

Fig. 2 is a broken edge-view thereof;

Fig. 3 is a broken rear-view thereof;

Fig. 4 is a view in longitudinal section taken on the line 4—4 of Fig. 1 but on a larger scale;

Fig. 5 is a view corresponding to Fig. 4 but showing the slide-member as tilted with respect to the body-member as during assembly or to release the strap;

Fig. 6 is a broken perspective view showing the body-member attached to the fixed-end of a strap and the free-end of the said strap threaded through the slide-member, the two said members being in position just preparatory to assembly;

Fig. 7 is a broken perspective view showing the next assembly step in which the slide-member is threaded through the slot in the body-member;

Fig. 8 is a perspective view of the slide-member, detached; and

Fig. 9 is a similar view of the body-member, detached.

The particular slide-buckle herein chosen for 55

the purpose of illustrating the present invention includes two main buckle-members 10 and 11. For convenience of description the buckle-member 10 may be designated as the body-member and the buckle-member 11, for the same reason, may be designated as the slide-member.

The body-member 10 comprises a top-bar 12 functioning as a strap-gripping portion, a bottom-bar 13 and two integral corresponding side-bars 14—14. The said top-bar 12, bottom-bar 13 and side-bars 14—14 define a slot 15 which is adapted to receive the slide-member 11 and portions of a strap, as will hereinafter appear.

As will be observed especially well in Figs. 6 and 15, the top-bar 12 of the body-member 10 has its central portion rearwardly offset and the integral side-bars 14—14 extend rearwardly with respect to both the said top-bar 12 and the bottom-bar 13. The body member 10 may be conveniently struck up from sheet metal and preferably the lower edge of the bottom-bar 13 is formed with a series of rearwardly-and-upwardly-extending clamping-fingers 16 which are designed and adapted to clamp the fixed-end 17 of a strap 20 against the opposed rear face of the bottom-bar 13 of the body-member 10 as is especially well shown in Figs. 4 and 5.

The slide-member 11 may be conveniently struck up from sheet metal and includes a top-bar 19, a bottom-bar 20 and two side-bars 21—21 integrally uniting the said top-bar 19 and bottom-bar 20 at their respective opposite ends. The said top-bar 19, bottom-bar 20 and side-bars 21—21 define a slot 22 into which upwardly projects a strap-gripping portion in the form of a gripping-tongue 23 formed integral with the bottom-bar 20. Preferably and as shown, the side-bars 21—21 of the slide-member 11 are rearwardly bowed and the gripping-tongue 23 is reversely or forwardly bowed.

The slide-member 11 is sufficiently narrow to fit between the respective inner faces of the side-bars 14—14 of the body-member 10 and hence is sufficiently narrow to be extended into the slot 15 in the said body-member.

In assembling the buckle-members 10 and 11 with each other and with a strap such as the strap 18, the fixed-end 17 of the strap is first inserted downwardly between the back face of the bottom-bar 13 of the body-member 10 and the front faces of the various clamping-fingers 16 thereof. The said clamping-fingers are bent forwardly so as to firmly grip the fixed-end 17 of the strap prior to assembling the slide-member 11 with either the said strap or with the body-

member 10. The free-end 24 of the strap 18 may now be threaded upwardly through the slot 22 in the slide-member 11 as is indicated by full lines in Figs. 6 and 7. The top-bar 19 of the slide-member 11 may now be inserted from front to rear through the slot 15 in the body-member 10 in the manner indicated in Figs. 5 and 7, after which the free-end 24 of the strap 18 may be threaded downwardly between the top-bar 12 of the body-member 10 and the top-bar 19 of the slide-member 11 as is indicated by full lines in Fig. 5 and by broken lines in Fig. 7. The free-end 24 of the strap 18 may now be led upwardly rearwardly of the top-bar 19 of the slide-member 11 and attached to whatever garment is desired.

Usually and prior to being inserted through the slot 22 in the slide-member 11 as above described, the free-end 24 of the strap 18 will be threaded through the suspension-loop 25 of a button-loop 26 or the like which may be hooked, so to speak, over a button of a garment such, for instance, as the button commonly employed upon bibs of overalls.

When tension or weight is applied to the button-loop 26, the slide-member 11 will both tilt and slide from the position in which it is indicated in Figs. 5 and 7 into substantially the position in which it is shown particularly well in Fig. 4, with the effect of firmly clamping the adjacent portion of the strap 18.

The portion of the free-end 24 of the strap 18 adjacent the body-member 10 and the slide-member 11 will now be clamped against slippage both by deflection and by a pinching action occurring between the bottom-bar 20 of the slide-member 11 and the bottom-bar 13 of the body-member 10 as well as by the gripping-tongue 23 of the slide-member 11 which will serve to measurably deflect the strap 18 against the upper forward corner of the top-bar 12 of the body-member 10, as is especially well shown in Fig. 4.

Should it be desired to release the grip of the slide-buckle upon the free-end 24 of the strap 18 for the purpose of either raising or lowering the button-loop 26, the slide-member 11 may be slid downwardly with respect to the body-member 10 or may be tilted into the position indicated in Figs. 5 and 7 to thereby release the grip upon the strap.

By means of the present invention, the slide-buckle may be assembled by merely inserting the slide-member 11 through the slot 15 in the body-member 10, thus obviating the need for permanent mechanical connection between the parts and with a consequent saving in cost of assembly.

Furthermore, by means of the present invention, the fixed end of a strap may be attached to the body-member 10 prior to the assembly of the buckle, and while the said body-member is free of encumbrances with the obvious advantage of time and labor savings.

The invention may be carried out in other specific ways than those herein set forth without departing from the spirit and essential characteristics of the invention, and the present embodiments are, therefore, to be considered in all respects as illustrative and not restrictive, and all

changes coming within the meaning and equivalency range of the appended claims are intended to be embraced therein.

I claim:

- 5 1. A slide-buckle comprising: a first buckle-member having two spaced-apart end-bars and two complemental side-bars which together with the said end-bars define a slot through the first buckle-member; a second buckle-member cooperating with the said first buckle-member and also having two spaced-apart end-bars and two laterally-spaced-apart side-bars defining a slot through the second buckle-member; one of the said buckle-members being narrower than the slot in the other of said buckle-members and extending through the last-mentioned slot between the side-bars bordering the same for sliding movement with respect to the other of said buckle-members; and one of the end-bars of one of the said buckle-members being provided with a gripping-tongue extending toward the other complemental end-bar and extending over the face of one of the end-bars of the other of said buckle-members to grip a strap therebetween.
- 10 2. A slide-buckle comprising: a first buckle-member having two spaced-apart end-bars and two complemental side-bars which together with the said end-bars define a slot through the first buckle-member; a second buckle-member cooperating with the said first buckle-member and also having two spaced-apart end-bars and two laterally-spaced-apart side-bars defining a slot through the second buckle-member; the said second buckle-member being narrower than the slot in the said first buckle-member and extending through the said slot between the side-bars bordering the same for sliding movement with respect to the said first buckle-member; and one of the end-bars of the said second buckle-member being provided with a gripping-tongue extending toward the other end-bar of the second buckle-member and extending over the face of one of the end-bars of the said first buckle-member to grip a strap therebetween.
- 15 3. A slide-buckle comprising: a first buckle-member formed integrally of sheet metal and having a top-bar shaped to provide a strap-gripping portion, a bottom-bar formed with bendable strap-gripping fingers, and two side-bars which together with the said top- and bottom-bars define a slot through the first buckle-member; and a second buckle-member formed integrally of sheet metal and narrower than the slot through the said first buckle-member and extending through the said slot in the first buckle-member, the said second buckle-member also having a top-bar, a bottom-bar and two integral side-bars which together with the said top- and bottom-bars define a slot through the second buckle-member; and the said second buckle-member being formed with a gripping-tongue extending upwardly from its bottom-bar and overlapping the top-bar of the said first buckle-member to grip the running-portion of a strap therebetween.
